Emery M. Hamilton

BY J. P. Fitch

ATTORNEY

UNITED STATES PATENT OFFICE.

EMERY M. HAMILTON, OF NEW YORK, N. Y.

TYPE-WRITING MACHINE.

SPECIFICATION forming part of Letters Patent No. 357,920, dated February 15, 1887.

Application filed December 2, 1886. Serial No. 220,494 (No model.)

To all whom it may concern:

Be it known that I, EMERY M. HAMILTON, of the city, county, and State of New York, and a citizen of the United States, have invented a new and useful Device for Intermittently Rotating the Feed-Rollers in Type-Writing Machines, of which the following is a full, clear, and exact description, reference being had to the accompanying drawings, forming part of this specification.

Figure 1 is a plan of a pair of feed-rollers with my new device for rotating them attached, and the remaining figures, from 2 to 7, inclusive, are detail drawings of detached parts, to be fully explained.

In type-writing machines there is what is called the "carrier," the office of which is to carry the paper over the point where the printing-impressions are made by the type in lines from one side to the other of the paper, and also to move the paper directly through the carrier perpendicularly to the lateral or side movement to form successive lines of printing. This direct movement is accomplished by feed-rollers forming a part of the carrier, between which the paper passes, the roller being, after this printing of each line, rotated a sufficient distance to carry the paper forward into position for the next succeeding line.

My invention relates to the device by means of which this intermittent rotation may be conveniently accomplished by the operator; and it consists in the devices hereinafter described and claimed.

A represents the carrier formed of a base-plate, *a*, two pillow-blocks, *b* *b'*, one at each end, and a pair of rollers, *B* and *C*, journaled in the said pillow-blocks. One end of the axial shaft *c* of the roller *B* projects beyond the pillow-block *b'*, in which it is journaled, and on this projecting end is fixed a ratchet-wheel, *d*, and outside of this ratchet-wheel is a loose pulley or wheel, *e*. On the extremity of the shaft is fixed a band-wheel, *f*. Pivoted on the inner face of the loose wheel *e* is a ratchet, *g*; arranged as shown in full lines in Fig. 3 and in dotted lines in Fig. 2, so that it will ride over the teeth of the ratchet-wheel

d when said wheel is rotated in one direction, 50 and will engage the said teeth when rotated in the opposite direction.

h is a thumb-piece formed on the wheel *e* as a convenient means for rotating or rocking the said wheel on the shaft *c*. The ends of 55 this thumb-piece extend out in either direction from the wheel, as shown in the drawings, and one end is weighted, so as to hold the wheel in its normal position, which is with the ratchet *g* resting on the lug *i*.

e' is the segment of a cylindrical sleeve, which projects from the inner face of the wheel *e* at its periphery over the pillow-blocks *b'*, and is so proportioned and arranged relatively to the pillow-block as to limit the movement 60 of the wheel *e* in either direction by the ends of the segment *e'* striking against the end of the pillow-block, so as to move the wheel *c* one tooth or any desired given number of teeth at each movement forth and back of the 65 said wheel. In the drawings the movement of a single tooth is represented. This device constitutes an efficient stop to limit the movement of the wheel *c*, as described; but any other suitable stop for the purpose may be 70 used.

i is a lug or projection on top of the pillow-block *b'*, which is so placed relatively to the ratchet *g* that when the wheel is in the position shown in Fig. 2 the ratchet will ride up 80 on the said lug, and be thereby held out of engagement with the ratchet-wheel *d*, and the roller *B* may then be rotated in either direction without obstruction.

The feeding of the paper, which is understood as being held between the rollers, is accomplished by the operator by rocking the wheel *e* into the position shown in Fig. 3 from the normal position shown in Fig. 2, the ratchet engaging the ratchet-wheel and rotating the said wheel, and of course the roller *B*, a distance equal to the spaces between the teeth of the ratchet-wheel, which should be equal to the desired distance between the centers of the lines of printing.

When the wheel *e* is in its normal position, as shown in Fig. 2, with the ratchet *g* resting on the pin *i*, the ratchet-wheel *d*, and of course

the roller B, are free to move in either direction.

What I claim as my invention, and desire to secure by Letters Patent, is—

5 The combination of the roller B, journaled in the described carrier-frame, the ratchet-wheel d, fixed on the shaft c, the loose wheel e, to which is pivoted the ratchet g, arranged to

engage said ratchet-wheel, and the lug i on the pillow-block b', all as and for the purpose described.

EMERY M. HAMILTON.
